UNITED STATES PATENT OFFICE.

JOSEPH C. WHISLER AND ISMA S. WHISLER, OF PERU, INDIANA.

UNIVERSAL JOINT.

1,294,583.

Specification of Letters Patent. Patented Feb. 18, 1919.

Application filed May 24, 1918. Serial No. 236,376.

To all whom it may concern:

Be it known that we, JOSEPH C. WHISLER and ISMA S. WHISLER, citizens of the United States, residing at Peru, in the county of Miami and State of Indiana, have invented certain new and useful Improvements in Universal Joints, of which the following is a specification, reference being had therein to the accompanying drawings.

10 This invention relates to universal joints, and has for its object the construction of an efficient and durable joint that will always run true and give satisfaction to the user.

With this and other objects in view, the 15 invention consists of certain novel constructions, combinations, and arrangements of parts, as will be hereinafter fully described and claimed.

In the drawings:

20 Figure 1 is a view in side elevation of a joint constructed in accordance with the present invention.

Fig. 2 is a longitudinal sectional view of the joint shown in Fig. 1.

25 Fig. 3 is a sectional view taken on line 3—3, Fig. 2 and looking in the direction of the arrows.

Fig. 4 is an end view looking at the large end of the primary section of the joint.

30 Fig. 5 is a transverse, sectional view through the center of the auxiliary section of the joint.

Fig. 6 is a view in side elevation of the auxiliary section of the joint.

35 Referring to the drawings by numerals, 1 designates the body and 2 the sleeve of the primary section. 3 designates the body and 4 the sleeve of the auxiliary section of the joint.

40 The body 1 is provided with a screw 5 and with an internally-threaded portion 6.

The auxiliary section has formed in its body 3 ball-receiving sockets 7 that register with sockets 8 formed in the inner face of 45 the body 1 of the primary section (Fig. 2).

Each socket 7 is provided with a central raised portion 9, and normally resting upon the central portion 9, in each socket, is a ball 10; each socket is elongated relative to 50 the longitudinal axis of the joint and each ball is permitted to roll in each socket; each socket is concentric to the center of the auxiliary section.

55 The primary locking ring 11 is threaded upon the threaded portion 6, the inner face of ring 11 bearing against the rounded outer

face of the auxiliary section, and said ring is provided with small sockets 12 for receiving a tool to easily rotate the ring, to take up wear and keep the auxiliary section in proper 60 position within the primary section. In the screw-threaded portion 6 of the primary section is formed a socket 13 that receives the lug 14 on the lock washer 15. An auxiliary ring 16 is threaded upon the threaded-por- 65 tion 6 against lock washer 15, Fig. 2.

A cap or cover 17 is slidably mounted upon the sleeve portion 4 of the auxiliary section, and a felt gasket or packing 18 is carried in the annular groove portion 19 of 70 the cap or cover 17, forming a tight joint between cap 17 and the outer face of the body 1 of the primary section. The cap 17 is provided with an inwardly-extending flanged portion 20, and a clamping band 21, 75 provided with bolt 22, is screwed upon the threaded portion 23 for holding the cap 17 snugly against the primary section of the joint, whereby a very tight fit is secured for preventing oil from spilling out of the joint, 80 and at the same time, preventing dust or foreign substances from working into the joint, keeping the joint very clean for the maximum efficiency thereof. Besides screw 5, we provide oil receiving apertures 5^a for 85 forcing lubricant into the joint and facilitating the entire lubrication of the device.

The balls 10 will permit sufficient free movement of the primary and auxiliary sections, yet said balls will lock said sections together, and by means of the rings 11 and 16, and the lock washer 15, the sections will be retained spaced close together to a nicety for producing a very efficient structure. 95

We wish it to be understood that we reserve the right to make such alterations, modifications, and changes as shall fairly fall within the scope of the appended claims, and as will be obvious to one skilled in the art to which 100 this invention relates.

What we claim is:

1. In a universal joint, a combination, of a primary section, an auxiliary section positioned in said primary section, said primary section provided on its inner face near one end with a threaded portion, said threaded portion provided with a longitudinally-extending slot, a primary ring threaded upon the threaded portion of said primary section and engaging the outer face of said auxiliary section, a lock washer provided 105

with a lug, said lug extending into said slot, and an auxiliary sleeve threaded upon said threaded portion of the primary section and pressing against said lock washer.

5 2. In a universal joint, the combination, of a primary and an auxiliary section, a primary and an auxiliary ring in said primary section and surrounding said auxiliary sec-

tion, and a lock washer provided with means for preventing rotation thereof within said ¹⁹ primary section, said lock washer interposed between said primary and auxiliary rings.

In testimony whereof we hereunto affix our signatures.

JOSEPH C. WHISLER.
ISMA S. WHISLER.
